HEATER

Henry J. De N. McCollum, Chicago, Ill.; Thelma McCollum executrix of said Henry J. De N. McCollum, deceased

Application October 7, 1942, Serial No. 461,122

10 Claims. (Cl. 126—116)

1 The present invention relates to heaters, particularly of the internal combustion type and is directed more specifically to an internal combustion type heater well suited for use in aircraft or other vehicles where high heat output together with high efficiency should preferably be obtained from a structure of minimum size and weight. A heater of this general type is shown and described in my copending application, Serial No. 447,345, filed June 17, 1942, for Heating apparatus.

It is one of the objects of the present invention to provide a novel internal combustion heater of the aircraft type which is extremely light in weight and economical to manufacture.

Yet another object of the present invention is to provide an internal combustion heater of extremely simple construction which is so arranged as to avoid the formation of hot spots within the heat exchange system.

Yet another object of the present invention is to provide a novel heater which burns a mixture of liquid fuel and air and quickly exchanges the heat of combustion to a moving fresh air stream.

Still another object of the present invention is to provide a novel heater having the above-mentioned advantages which is extremely well adapted to be manufactured by quantity production methods.

Yet another object of the present invention is to provide a novel aircraft heater which uses a length of corrugated tubing as one of the principal elements of construction.

Other objects and advantages will become apparent from the following description of a preferred embodiment of my invention which is illustrated in the accompanying drawing.

In the drawing, in which similar numerals refer to similar parts throughout the several views,

Fig. 1 is a side view of a heater embodying the present invention.

Fig. 2 is a longitudinal sectional view of the heater illustrated in Fig. 1, and

Fig. 3 is a transverse sectional view which may be considered as taken in the direction of the arrows along the line 3—3 of Fig. 2.

The heater of the present invention is supplied with a combustible mixture which is taken into the heater through an intake fitting 10. This mixture, preferably composed of vaporized liquid fuel and air, may be supplied by a carburetor specially provided for the heater, or it may be supplied from some already present source of combustible mixture, such as the supercharger

2 casing of one of the engines used to propel the aircraft.

The intake fitting 10 is provided with a bundle of small diameter tubes 12 formed of a material having good heat conducting properties. The openings through the tubes, together with the spaces between adjacent tubes, provide passages of sufficient capacity so that little restriction is offered to the flow of combustible mixture therethrough. These tubes, however, prevent flame from flashing back into the mixture induction pipe connected to the fitting 10 in a manner explained in the before mentioned co-pending application.

13 After the mixture has passed through the tubes 12, it enters an elbow portion 14 of the fitting 10 where combustion of the mixture is initiated. The ignition is accomplished by means of a temporarily heated igniter 16 of the electrically energized hot wire type. Such an igniter is described in the before mentioned co-pending application. The elbow 14 also is equipped with a reigniter 18 of the spiral sheet type, also described in the above mentioned co-pending application. This reigniter is heated to a high temperature by the flame and, therefore, serves to reignite the combustible mixture if combustion should for any reason fail after the hot wire igniter 16 has been deenergized.

30 Preferably, the mixture should enter the elbow portion of the fitting through a generally cylindrical cap 20 having a plurality of radially arranged ports 22 formed by striking vanes 21 inwardly from the side walls thereof. The vanes project inwardly at an angle and, therefore, the mixture passes from the cap with a swirling motion, thus insuring good turbulence at the point of ignition.

40 From the elbow portion 14 of the fitting 10, the flame projects into a sheet metal structure indicated generally by the numeral 26. This structure is formed of a generally cylindrical internal member 28, formed preferably of stainless sheet steel, provided with oppositely positioned longitudinally extending slots which form a combustion space 30 and an exhaust passage 32. These slots are generally square in cross section and extend from end to end of the internal member. The cylindrical side walls extending between the combustion space and exhaust passage are provided with a multiplicity of perforations 34, while the interior of the internal member is filled with acoustic damping material 35, such as glass wool or stainless steel wool, for instance,

which operates in a manner to be described presently.

The internal member 28 is enclosed within a bellows type, comparatively deeply circumferentially corrugated, heat exchange jacket 36 which is substantially co-extensive in length with the internal member. Preferably, this corrugated member is also formed of stainless steel. The corrugated heat exchange jacket 36 has the inner edges of its corrugations spot or seam welded to the cylindrical surfaces of the muffler member 28. The two members thus provide a plurality of inner circumferentially extending passages 38 between the corrugations which communicate with both the combustion space 30 and the exhaust passage 32.

A generally cylindrical outer shell 40 encloses the corrugated heat exchange jacket 36 and is arranged with its inner surface closely adjacent the outer edges of the corrugations. The corrugated jacket 36 and the outer shell 40, therefore, form a plurality of outer passages 42 between the corrugations which extend circumferentially of the heater.

Directly opposite the combustion space 30, the outer sheet metal jacket 40 is shaped to provide a flared cold air inlet fitting 44 extending from end to end of the corrugated jacket 36, thus permitting cold air flowing inwardly to be distributed over the outer surface of the portion of the corrugated jacket 36 located directly at the combustion space 30. On the opposite side of the heater, the shell 40 is shaped to provide a similar outlet fitting 46 leading from the shell directly at the exhaust passage 32.

The ends of the internal member 28 and the corrugated heat exchange jacket 36 are welded to end plates 48 and 50, preferably formed of stainless sheet steel, which prevent gas communication between the internal and external portions of the corrugated jacket 36. The ends of the surrounding shell 40 are also welded to end plates 52 and 54 which insure that the air entering the cold air inlet fitting 44 shall escape only through the outlet fitting 46.

The elbow portion 14 of the fitting 10 is secured to the end plate 52 directly at one end of the combustion space 30 and an opening through the plate 48 is made to permit flame issuing from the elbow portion 14 to project longitudinally into this combustion space. A similar exhaust fitting 56 is connected to the opposite end plate 50 at the end of the exhaust passage 32 and an opening is provided through the end plate 54 to permit exhaust gases collected in the passage 32 to flow outwardly through the fitting. These exhaust gases may be passed through a pipe connected to the fitting to a position outside the airplane, or other vehicle in which the heater is installed.

The end plates 52 and 54 are provided with openings through which the fittings 10 and 56 pass and these end plates are sealed to the fittings around these openings to prevent the escape of hot air.

The above described device operates in the following manner:

Combustible gases enter the fitting 10 and pass through the bundle of tubes 12 and thence outwardly through the ports 22 in the cap 20 into the elbow portion 14 where they are ignited by the igniter 16. The resulting combustion quickly raises the temperature of the reigniter 18 sufficiently so that the igniter 16 may be de-energized, since any subsequent momentary fail-

ure of combustion will result in the flame being rekindled by the hot re-igniter 18.

The flame thus produced is projected into the combustion space 30 and the hot products of combustion flow outwardly in both directions into the passages 38 between adjacent convolutions of the corrugated jacket 36. These hot products of combustion flow generally circumferentially in opposite directions on opposite sides of the heater until they reach the exhaust passage 32. Here they are collected and passed outwardly through the exhaust fitting 56. The perforations 34 in the side walls of the muffler structure 28, together with the acoustic damping material located within this structure serve to damp out periodic pulsations and, therefore, insure a steady combustion rate, thus effectively preventing the phenomenon known as "motor boating."

The hot products of combustion within the corrugated heat exchange jacket 36 heat the walls of this jacket to a high temperature and this heat is exchanged to the fresh air stream flowing inwardly from a blower or ram to the fitting 44, the fresh air impinging directly against the portion of the corrugated tubing which forms one wall of the combustion space 30. After impinging against this high temperature portion of the corrugated tubing, the air flows outwardly and circumferentially in both directions and leaves the heater at the hot air outlet fitting 46.

The above arrangement, it should be noted, is such that not only does the coldest air flow over the hottest portion of the corrugated jacket 36, but also this cold air impinges directly against the hottest portion thereof. This is important inasmuch as the heat exchange rate between a hot surface and an air stream increases greatly as the angle of attack of the air moving against the hot surface approaches the vertical. The arrangement thereby insures that the portion of the corrugated tubing which forms one wall of the combustion space will receive by far the greatest cooling effect, thus effectively preventing this portion of the tubing from overheating. It also provides an extremely efficient exchange of heat at the point where the temperature differential on opposite sides of the heat exchanger is the greatest.

While I have shown and described a particular embodiment of my invention, it will be apparent to those skilled in the art that numerous modifications and variations may be made without departing from the underlying principles of the invention. I therefore desire, by the following claims, to include within the scope of the invention all such modifications and variations by which substantially the results thereof may be obtained by substantially the same or equivalent means.

I claim:

1. In an internal combustion heater, a generally cylindrical interior member having re-entrant portions in the side wall thereof to form a combustion space and an exhaust passage, means for supplying a combustible mixture to said combustion space, means for conveying products of combustion from said exhaust passage, a length of corrugated tubing surrounding said interior member so that the spaces between corrugations on the inner surface of said tubing together with said interior member provide a plurality of passages connecting said combustion space to said exhaust passage, said corrugated tubing also forming one wall of said combustion space and one wall of said exhaust passage, a

jacket surrounding said corrugated tubing, said jacket having inlet and outlet openings, and means for supplying air to said inlet opening, said inlet opening being located substantially directly opposite said combustion space so that air entering through said inlet opening will impinge directly against the portion of said corrugated tubing which forms one wall of said combustion space.

2. In an internal combustion heater, an interior member having re-entrant portions in the side walls thereof to form a combustion space and an exhaust passage, means for supplying a combustible mixture to said combustion space, means for conveying products of combustion from said exhaust passage, said interior member being hollow and having perforations in a portion of the side wall thereof, a quantity of acoustic damping material located within said interior member, a corrugated covering for said interior member so that the spaces between corrugations on the inner surface of said covering together with said interior member provide a plurality of passages connecting said combustion space to said exhaust passage, said corrugated covering also forming one wall of said combustion space, a jacket surrounding said corrugated covering, said jacket having inlet and outlet openings, and means for supplying air to said inlet opening, said inlet opening being located substantially directly opposite said combustion space so that air entering through said inlet opening will impinge directly against the portion of said corrugated covering which forms one wall of said combustion space.

3. In an internal combustion heater, an interior member having re-entrant portions in the side walls thereof to form a combustion space and an exhaust passage, means for supplying a combustible mixture to said combustion space, means for conveying products of combustion from said exhaust passage, a corrugated covering for said interior member so that the spaces between corrugations on the inner surface of said covering together with said interior member provide a plurality of passages connecting said combustion space to said exhaust passage, said corrugated covering also forming one wall of said combustion space, a jacket surrounding said corrugated covering, said jacket having inlet and outlet openings, and means for supplying air to said inlet opening, said inlet opening being located substantially directly opposite said combustion space so that air entering said inlet opening will impinge directly against the portion of said corrugated covering which forms one wall of said combustion space.

4. In an internal combustion heater, a generally cylindrical interior member having re-entrant portions in the side walls thereof to form a combustion space and an exhaust passage, means for supplying a combustible mixture to said combustion space, means for conveying products of combustion from said exhaust passage, said interior member being hollow and having perforations in a portion of the side wall thereof, a quantity of acoustic damping material located within said interior member, a length of corrugated tubing surrounding said interior member so that the spaces between corrugations on the inner surface of said tubing together with said interior member provide a plurality of passages connecting said combustion space to said exhaust passage, said corrugated tubing also forming one

wall of said combustion space and one wall of said exhaust passage, a jacket surrounding said corrugated tubing, said jacket having inlet and outlet openings, and means for supplying air to said inlet opening, said inlet opening being located substantially directly opposite said combustion space so that air entering through said inlet opening will impinge directly against the portion of said corrugated tubing which forms one wall of said combustion space.

5. In an internal combustion heater, a generally cylindrical interior member having re-entrant portions in the side wall thereof to form a combustion space and an exhaust passage, means for supplying a combustible mixture to said combustion space, means for conveying products of combustion from said exhaust passage, said interior member being hollow and having perforations in a portion of the side wall thereof, a quantity of acoustic damping material located within said interior member, a length of corrugated tubing surrounding said interior member so that the spaces between corrugations on the inner surface of said tubing together with said interior member provide a plurality of passages connecting said combustion space to said exhaust passage, means sealing the ends of said tubing to the ends of said interior member, said corrugated tubing also forming one wall of said combustion space and one wall of said exhaust passage, a jacket surrounding said corrugated tubing, means sealing said jacket at its ends, said jacket having inlet and outlet openings, and means for supplying air to said inlet opening, said inlet opening being located substantially directly opposite said combustion space so that air entering said inlet opening will impinge directly against the portion of said corrugated tubing which forms one wall of said combustion space.

6. In an internal combustion heater, an interior member having re-entrant portions therein to form a combustion space and an exhaust passage, means for supplying a combustible mixture to said combustion space, means for conveying products of combustion from said exhaust passage, a corrugated enclosure for said interior member so arranged with the corrugations extending circumferentially that the spaces between corrugations constitute fluid conducting passages connecting said combustion space to said exhaust passage, means sealing the ends of the corrugated member to the ends of the interior member, said corrugated member also forming one wall of said combustion space and one wall of said exhaust passage, a jacket surrounding said corrugated member, means sealing said jacket at its ends, said jacket having inlet and outlet openings, and means for supplying air to said inlet opening, said inlet opening being located closely adjacent said combustion space.

7. In an internal combustion heater, a generally cylindrical interior member having re-entrant portions in the side wall thereof to form a combustion space and an exhaust passage, means for supplying a combustible mixture to said combustion space, means for conveying products of combustion from said exhaust passage, a length of corrugated tubing surrounding said interior member with the corrugations extending circumferentially so that the spaces between the corrugations in the inner surface of said tubing constitute passages connecting said combustion space to said exhaust passage, means sealing the ends of said tubing to the ends of said interior member, said

corrugated tubing also forming one wall of said combustion space and one wall of said exhaust passage, a jacket surrounding said corrugated tubing, means sealing said jacket at its ends, said jacket having inlet and outlet openings and means for supplying air to said inlet opening, said inlet opening being located closely adjacent said combustion space.

8. In an internal combustion heater, a length of generally circumferentially corrugated tubing, means located within said length of corrugated tubing to form with said tubing a plurality of circumferentially extending passages, a jacket enclosing said length of corrugated tubing to form with the exterior surface of said tubing a plurality of circumferentially extending passages, means to introduce hot gases between the inner surface of the corrugated tubing and the means located within said tubing, and means connected to the jacket to introduce air between said jacket and said length of corrugated tubing at a point closely adjacent that at which the hot gases are introduced.

9. In an internal combustion heater, a length of generally circumferentially corrugated tubing, means located within said length of corrugated tubing to form with said tubing a plurality of inner circumferentially extending passages, a jacket enclosing said length of corrugated tubing to form with the exterior surface of said tubing a plurality of circumferentially extending passages,

means to maintain combustion in said inner passages along a line extending transversely of said corrugations, and means connected to the jacket to introduce air into said outer passages along a line adjacent the first said line.

10. In an internal combustion heater, a length of generally circumferentially corrugated tubing, means located interiorly of said tubing for forming with said tubing a pair of axially extending passages at opposite sides of the heater from each other and a set of circumferentially extending passages between the corrugations connecting said axially extending passages, means located exteriorly of said tubing for forming with said tubing a second pair of axially extending passages at opposite sides of the heater from each other and a second set of circumferentially extending passages interspersed with the circumferentially extending passages of said first named set and connecting together the axially extending passages of said second pair, each of said axially extending passages of said second pair being located closely adjacent one of the axially extending passages of said first named pair, means connected to said tubing for introducing hot gases into one of the passages of one of the pairs, and means connected to said second named means for introducing fluid to be heated into the adjacent passage of the second pair.

HENRY J. DE N. McCOLLUM.
